DESIGN FOR A BOTTLE CLOSURE

Elta Simmons, Akron, Ohio, assignor to The
Pyramid Rubber Company, Ravenna, Ohio

Application May 20, 1942, Serial No. 106,957

Term of patent 14 years

To all whom it may concern:

Be it known that I, Elta Simmons, a citizen of the United States, residing at Akron, in the county of Summit and State of Ohio, have invented a new, original, and ornamental Design for a Bottle Closure, of which the following is a specification, reference being had to the accompanying drawing, forming part thereof, wherein:

Figure 1 is a side elevational view of the bottle closure showing my new design.

Figure 2 is an end elevational view of the same.

Figure 3 is a top plan view of the same.

Figure 4 is a bottom plan view.

I claim:

The ornamental design for a bottle closure, substantially as shown.

ELTA SIMMONS.
